UNITED STATES PATENT OFFICE.

CHARLES R. LAMBERT, OF DETROIT, MICHIGAN, ASSIGNOR TO CLAYTON & LAMBERT MANUFACTURING COMPANY, OF DETROIT, MICHIGAN, A CORPORATION OF MICHIGAN.

PROTECTING-SHIELD FOR TORCHES.

1,258,229.

Specification of Letters Patent.

Patented Mar. 5, 1918.

Application filed March 8, 1917. Serial No. 153,252.

To all whom it may concern:

Be it known that I, CHARLES R. LAMBERT, a citizen of the United States of America, residing at Detroit, in the county of Wayne and State of Michigan, have invented certain new and useful Improvements in Protecting-Shields for Torches, of which the following is a specification, reference being had therein to the accompanying drawings.

10 The invention relates to torches designed for use in soldering, splicing wires, etc., and it is the object of the invention to obtain a construction of protecting shield which may be easily applied to the torch 15 and which permits of readily inserting and withdrawing the work. To this end the invention consists in the construction as hereinafter set forth.

In the drawings:

20 Figure 1 is an elevation of a torch with the protecting shield applied thereto;

Fig. 2 is a perspective view of the shield detached;

25 Fig. 3 is a section on line $x-x$ Fig. 1; Fig. 4 is a section on line $y-y$ Fig. 1.

A is a torch, which as specifically shown, is provided with a wick-tube B and a blow-pipe C, the latter extending through the font for the liquid fuel, and having an upwardly-projecting portion with the inwardly-bent nozzle portion D in proximity to the flame. E is a flexible tube connected with the lower end of the tube C, through which air is blown.

35 To protect the flame and to conserve the heat when the torch is in use, I have provided a detachable shield F. This is formed with a sleeve portion G for fitting over the wick-tube B, and above the sleeve the shield 40 is expanded to form a cylindrical chimney portion H for surrounding the flame. There is also a laterally-extending portion I, which is in line with the blow-pipe and is provided with a transversely-extending and down-45 wardly-opening slot J for the insertion of the work. The cylindrical portion H is also provided with a laterally-opening slot K for the insertion of work to be placed directly in the flame of the torch, and a slide-50 able closure L is arranged to close the slot when the work is inserted. This closure has a projecting lip M for facilitating opening

of the same, and its inner end is cammed at N to automatically open the closure by the withdrawal of the work. O is an entrance 55 slot for the nozzle D when the shield is engaged with the torch, and this slot is provided with a lateral projection P forming in connection with the nozzle a bayonet lock for the closure.

In use, when it is desired to employ an intense heat, the work, such for instance as a wire splice Q, is inserted through the slot J into alinement with the blow-pipe. Air is then blown through the tube E, which 65 will deflect the flame laterally and cause it to impinge upon the work. Where a less intense heat is required the work may be inserted in the slot K by first placing it beneath the lip M, lifting the sliding shield 70 L and inserting through the slot K. This will bring the work directly into the flame from the torch, and after completion, a lateral movement will cause the cam N to open the slide L and permit the work to pass 75 out.

The construction as described can be easily manufactured from sheet-metal at low cost, and when applied to a torch will greatly increase its efficiency.

80 Another use to which my invention is adapted is the heating of soldering irons and other small tools, which may be supported directly on the top of the shield and heated by the flame from the torch and hot 85 gases passing upward therefrom.

What I claim as my invention is:—

1. The combination with a torch having a blow-pipe for deflecting the flame laterally, of a shield detachably engaging said 90 torch to form a chimney protection for the flame, said shield having a laterally-projecting portion in line with the blow-pipe, slotted for the reception of the work.

2. The combination with a torch provided 95 with a wick-tube and a blow-pipe for deflecting the flame laterally, of a shield having a sleeve portion for engaging said wick-tube, a chimney portion for inclosing the flame and a laterally-projecting portion for 100 housing the deflected blow-pipe flame, said shield being slotted for the insertion of the work in both the direct and the deflected flame.

3. The combination with a torch having a wick-tube and a blow-pipe extending upward and bent inward to deflect the flame laterally, of a shield having a sleeve portion 5 for engaging said wick-tube, a chimney portion for inclosing the direct flame and a laterally-extending portion for housing the

deflected flame, said shield being slotted for the insertion of the work and also provided with a bayonet slot coöperating with the inwardly-projecting portion of the blow-pipe to form a lock.

In testimony whereof I affix my signature.
CHARLES R. LAMBERT.
